UNITED STATES PATENT OFFICE.

WILLIAM W. GOOD AND FRED H. BUCKMAN, OF CHICAGO, ILLINOIS.

DRAIN-PIPE PLUG.

1,275,419.

Specification of Letters Patent. Patented Aug. 13, 1918.

Application filed November 7, 1916. Serial No. 130,057.

To all whom it may concern:

Be it known that we, WILLIAM W. GOOD and FRED H. BUCKMAN, citizens of the United States, residing at Chicago, in the 5 county of Cook and State of Illinois, have invented certain new and useful Improvements in Drain-Pipe Plugs, of which the following is a specification.

This invention relates to plugs for use in 10 connection with waste openings of bath tubs, wash basins and laundry trays.

More specifically, it is the object of this invention to provide a device that is to be fixedly secured to the tub, basin or tray as 15 it may be, to retain at all times the rod rising from the plug of the outlet valve.

Further object of this invention resides in 20 a plurality of novel brackets adapted to be used in connection with this rod to support the same in connection with certain articles.

A still further object of this invention resides in the production of a device that will 25 accomplish the above set forth functions and will also obviate the use of the ordinary overflow opening.

A still further object of this invention resides in the production of a device of the kind above described that is simple in construction, efficient in operation and consists 30 of the minimum number of parts.

With these and other objects in view, this invention consists of certain novel constructions, combinations and arrangement of parts, as will be hereinafter fully described 35 and claimed.

In the accompanying drawings:

Figure 1 is a view of the improved device 40 in connection with a bath tub, a portion of the tub being shown in section as well as the fixtures thereof.

Fig. 2 is a top plan view of the improved brackets for retaining the device in connection with the bath tub fixtures, the operating rod shown in section.

Fig. 3 is a sectional view taken on line 3—3 of Fig. 1.

Referring to the parts by reference numerals, the hollow operating rod of the plug is designated by the numeral 10 having at 45 the upper end the hand engaging wheel or knob 11 and at the lower end thereof the plug section 12, the said section having alined slots 13 formed therein and a washer

14 secured thereto for engagement with the sides of the waste opening of a bath tub for 55 the obvious purpose. The pin 15 is secured to or made integral with the rod 10 adjacent the upper end thereof for a purpose to be hereinafter fully set forth. Complementary bracket sections are provided for the reception of the device in connection with a bath tub, the said bracket sections each comprising substantially semi-circular portions 16 and 17 and parallel portions 18 and 19. The two substantially semi-circular portions 60 16 are adapted to be passed about the supporting standard of the ordinary soap tray and the two substantially semi-circular portions 17 about the rod 10. These bracket members are retained in the position shown 65 in Figs. 1 and 2 by means of bolts 20. As is clearly shown in Fig. 2, the substantially semi-circular members 17 do not meet and therefore means is provided whereby the pin 15 on the rod 10 can be moved vertically 70 in Figs. 1 and 2, can be positioned on the upper edge of either of the substantially semi-circular members 17. It is obvious that 75 when the device is in a position as shown in Fig. 1, the waste opening is closed and when it is desired to open the same all that is necessary is to turn the rod 10 until the pin 15 thereon is in alinement with the space between the substantially semi-circular members 17 and then move the rod upwardly 80 until the pin 15 is above the bracket members and turn the rod 10 until the pin 15 is out of alinement with the spaced ends of the 85 substantially semi-circular members 17 and rest the same on the upper edges thereof.

It is obvious that minor changes may be made in the form and construction of this invention without departing from the material parts thereof. It is therefore not wished to confine the invention to the exact form herein shown and described, but it is wished to include all such as properly come within the scope claimed.

What we claim is—

The combination with a vertically movable outlet valve in a bath tub or the like, and a fixture disposed within said tub above the valve; of a rod rising from said plug 105 and having a radial pin, a pair of comple-

mentary bracket sections whereof each has two substantially semi-circular portions and two straight portions at opposite sides of one of them, and bolts through the straight portions of said sections whereby the intervening semi-circular portions are clamped to opposite sides of said fixture and the remaining semi-circular portions are caused to loosely surround said rod, leaving an open-

ing between their extremities through which 10 said pin may pass, as described.

In testimony whereof we affix our signatures in presence of two witnesses.

WILLIAM W. GOOD.
FRED H. BUCKMAN.

Witnesses:

RICHARD MATTHIES,
WILLIAM A. JACOBS, Jr.
